UNITED STATES PATENT OFFICE.

PHILIP S. MITTS AND WILLIAM J. WINSTON, OF SAGINAW, MICHIGAN, ASSIGNEES TO
MITTS & MERRILL, OF SAGINAW, MICHIGAN, A CORPORATION OF MICHIGAN.

DISINTEGRATING MACHINE.

Application filed February 26, 1925. Serial No. 11,873.

This invention relates to cutting and disintegrating machines commonly known as hogs and used for the mechanical reduction of a great variety of materials, such as 5 wood refuse, also other fibrous materials.

Our present improvement pertains to a hog of the type having flat bar knives on the periphery of the drum and traveling in close proximity to stationary cutter bars 10 mounted in the frame of the machine.

An object is to provide an improved arrangement of the knife blades on the drum, whereby they operate by beating and crushing the material, as well as by a shearing 15 action very similar to the action of the shear blades in bar-cutting alligator shears.

This result is accomplished by employing heavy flat blades arranged angularly with relation to the drum axis, the angular direction of successive blades preferably reversed, thereby reducing the tendency of the material being cut to force the drum endwise. 20

The invention also includes a new means for accurately setting or gauging the cutting 25 edge of the angularly disposed knife to its proper position and to prevent dislodgement of the drum knife. This gauging device also acts as a scraper to prevent material accumulating in the housing at the side edges of the drum rim. Such accumulation 30 has heretofore been a source of trouble, because the friction of the rapidly revolving drum edge against a mass of accumulated material is excessive and unless checked may cause fire. 35

With the foregoing and certain other objects in view which will appear later in the specifications, our invention comprises the devices described and claimed and the 40 equivalents thereof.

The flat bar knives have enormous strength to drive through very hard, tough and thick materials, and the outer faces of the knives, as well as the drum surfaces 45 between successive knives are shaped and arranged so that heavy chunks, immediately upon being faced off by a knife, and while feeding inward prior to the arrival of the next knife, slide upon a cam-like guiding 50 area of the drum. The effective guiding area establishes maximum depth of bite for the next knife. A more uniformly sized product and greater hourly capacity is thereby attained.

55 In the drawings Fig. 1 is a sectional side

elevation of a cutting hog embodying our improvements.

Fig. 2 is a side view of the drum carrying angularly disposed cutting knives.

Fig. 3 is a developed view of the working 60 face of the drum shown in Fig. 2.

Fig. 4 is a part sectional detail of the device for clamping the cutter knife to the rim of the drum and for adjusting the position of the backing support for the knife. 65

Fig. 5 is a part sectional side view showing the action of a knife on material being fed in.

Fig. 6 is a side view of a part of the drum rim with a diagonally disposed knife held 70 in place by our improved knife-gauging device.

Fig. 7 is a front view of the parts shown in Fig. 6.

Fig. 8 is a perspective view of the knife- 75 gauging device.

Fig. 9 is a perspective view of a knife and two gauging devices in position on a section of the rim.

As is clearly shown in the drawings the 80 hog consists in the usual frame 1 in which revolves the cylindrical drum 2 having cutting knives 3, 3^a etc. on its periphery. A plurality of fixed cutter bars 4, 5 and 6 are arranged in the frame around the lower part 85 of the periphery of the drum. The drum has a throat or hopper 7 for receiving material and a discharge outlet 8. The bottom of the throat 7 may be formed with a hinged door 9 carrying a cutter bar 10 at the base of the 90 throat 7, as is shown and described in co-pending application of Philip S. Mitts, Serial Number 703,658, filed Apr. 2, 1924, of which this application is a continuation in part. 95

As will be seen from Fig. 3, the knives extend the entire width of the face of drum 2. They are preferably angularly placed, alternate knives preferably having opposite angular inclinations. 100

The angular arrangement of the knives 3 and 3^a is preferred because it prevents the drum knife striking squarely into a wide chunk of material and thereby causing an unnecessary shock both to the machine and to the revolving drum knives. The angular position of the knives on the drum causes them to bite more gradually into the material, permitting the machine to operate more smoothly with a shearing cut. 105 110

Obviously, as is shown in Fig. 2, the two extremities 11 and 12 of the cutting edge 13 of knife 3 are at the same radial distance from the axis of the drum, and in 5 that part close to the advancing edge of the knife the grinding area of the drum is approximately cylindric, see "C" Fig. 9. Special arrangement is required, however, for the back edge of the knife to provide working clearance, as will later be explained.

Referring now to diagrammatic Fig. 5, a knife 3 is shown cutting into a heavy piece of work, which may be a thick plank of considerable width, even so wide as to almost 15 occupy the width of the throat 7. The advancing knife 3 bites into the material with a shearing cut and its outwardly extending advancing face also has a simultaneous crushing and breaking action upon the fibres 20 of the material as severed, the result of this combined cutting and breaking being that the material leaves the throat of the machine in a thoroughly shattered condition. In that respect the knife arrangement herein 25 shown combines the advantages of both a typical cutting hog and a beating machine. Obviously the force of the blows delivered by the knives is very great and consequently the knives must be of great strength and 30 durability and be strongly secured to the drum. To meet that requirement we make the knife from a flat steel bar, wide and thick.

We prefer to mount the knife 3 on the 35 rim 2 by means of countersunk head bolts 14 passing through elongated slots 15 in the rim 2.

In the back edge of each knife, as shown 40 in Figs. 3 and 4, sockets 16 are formed to receive the heads of concealed adjusting screws 17 threaded into openings in the rear wall or shoulder 18 of the cylinder.

The screws 17 are adjusted outwardly so 45 that the cutting edge of the knife 3 when placed in position against the screw heads will come to its proper cutting position on the drum. The knife is then clamped to the drum by bolts 14. Screw 17 prevents the knife 3 from moving backward should 50 the bolts 14 not be properly tightened.

The correct position of the cutting edge 55 of the knife 3 may be gauged by means of gauge members 19, Fig. 9. These gauge members are rectangular bars of steel notched at their outer ends 20, Fig. 8, to accurately fit the lower part of the front face of the knife. They are provided with countersunk recesses 21 on their outer faces and are inset into mortises 22 cut into the 60 side edges of the drum rim 2 and are located so that the gauges 19 when inset will hold the cutter bars 3 in their proper angular positions relative to the drum rim. Preferably the outer face of bar 19 projects laterally beyond the edge of the drum rim,

as shown at 23, Fig. 7. This projecting part of the bar acts as a clearance cutter or scraper to prevent such accumulation of material in the housing of the machine as might cause binding or beating. The pair of gauge 70 bars 19, 19 also prevents the knife 3 from moving forward should the bolts 14 not be properly tightened.

The purpose of the cam-like construction 75 of the drum rim, above described, is to control the depth of feed and prevent material, such as heavy timbers and the like, from feeding too far in toward the center of the drum and consequently causing the knife to attempt too deep a bite. By limiting the 80 depth of bite or cut, yet giving the material proper opportunity after each cut, to drop into place on the drum rim to receive the next cut, a more uniformly disintegrated product is secured, and the beating and 85 shattering action of the advancing knife face has full effect without choking. Consequently the guiding area of the drum face is an important aid to the combined beating and cutting action of the drum knives. With one end 11 of the knife advanced and 90 lowered from R' to R the area varies progressively from tapering or approximately conical at the back of one knife, to substantially cylindric at the throat C of the 95 following knife. The reason is as follows:

Referring again to Fig. 5, it will be seen 100 that between successive knives is an effective guiding area that extends from the outer surface or top of one knife 3^a to the inner edge of the advancing face of the next succeeding knife 3. If the knife bar were parallel with the axis of the drum, then 105 this guiding area obviously would be described by elements parallel with the axis, but the knife is preferably located on the drum with one end in advance of the other, as shown at X in Figs. 2 and 3. Consequently, in order to use a flat bar and to 110 secure proper clearance at the back edge, it is necessary to lower the heel 3^b of the advancing end of the knife so as to shorten 115 its radial distance R, making it less than the radial distance R' at the other end of the knife. The back edge is, therefore, 115 radially inclined with respect to the axis, although the working edge 13 is throughout its length substantially equidistant radially from the drum axis.

By so dropping and tilting the rear edge 120 without tilting the front working edge, we are enabled to employ a heavy straight plane-surface bar, gaining thereby the important advantages of cheapness for a given duty, and greater shearing effect on account 125 of greater permissible shear or angularity "X". The flat bar has great durability, for its face may be worn back a considerable distance before replacement is necessary. To secure the correct clearance it is not ab- 130

solutely essential to produce a radially inclined knife seat. It is sometimes advisable to gain the same effect, as regards back clearance, by cutting away the top surface 5 of the back edge of the knife, as indicated by dotted lines at $y-y$ in Fig. 9.

Having thus described our invention, what we claim and desire to secure by Letters Patent is:

- 10 In a machine of the character described, a revolving drum having flat straight-edged knives on the peripheral face thereof ex-

tending angularly across the drum, successive knives having opposite angular inclinations with respect to the axis of the 15 drum, each knife having a straight-edged material-beating face, those peripheral parts of the drum between successive knives warped to present alternately sloping surfaces, for the purposes set forth.

In testimony whereof, we affix our signatures.

PHILIP S. MITTS.

WILLIAM J. WINSTON.
